UNITED STATES PATENT OFFICE.

FREDERIC E. KIP, OF MONTCLAIR, NEW JERSEY.

DESIGN FOR A PILE FABRIC.

No. 38,610.

Specification for Design.

Patented June 4, 1907.

Application filed May 7, 1907. Serial No. 372,445. Term of patent 7 years.

To all whom it may concern:

Be it known that I, FREDERIC E. KIP, a citizen of the United States, residing at Montclair, county of Essex, State of New Jersey, have invented a new, original, and ornamental Design for a Pile Fabric.

The design is illustrated in the accompanying drawing which shows a face view thereof.

I claim,

The ornamental design for a pile fabric, as shown.

FREDERIC E. KIP.
